UNITED STATES PATENT OFFICE

SPENCER OTIS, OF BARRINGTON, ILLINOIS, ASSIGNOR TO THE LOCOMOTIVE TERMINAL IMPROVEMENT COMPANY, OF CHICAGO, ILLINOIS, A CORPORATION OF MAINE

METHOD OF RENOVATING LOCOMOTIVES

Application filed January 29, 1923. Serial No. 615,712.

This invention relates to a method of blowing off the boilers of steam locomotives as an incident to cleaning and repairing them.

The object of the invention is to provide a method of procedure whereby the time of evacuation of the contents of a locomotive boiler may be greatly reduced through the application of an influence from an extraneous source and without undue cost.

It has long been the practice to introduce water into a steam boiler through means of a steam injector operating upon the principle of releasing steam at high velocity, condensing it by bringing it into injector relation to feed water while maintaining its velocity, and causing it to take up the feed water and carry the latter into the boiler, notwithstanding the internal boiler resistance.

But this method, aside from having to do with the treatment of boilers that are in operation and already supplied with a complement of water, is slow, relatively inefficient, and expensive, and affords no substantial assistance in solving the problem of the present invention, which is to hasten the evacuation of a boiler by a boosting application of steam from an extraneous source under conditions which permit salvaging the heat units of the steam and thereby reducing the cost of steam consumption, and thereafter returning such heat units with water used in restoring the boiler to service.

In carrying out the present invention, in addition to the usual means employed for blowing off the contents of a boiler and salvaging the heat units of the blown off products as a preliminary to washing out and repairing the boiler, means are provided for delivering steam from an extraneous source, in such relation to the blowoff system as to greatly boost the flow of blown off products and add its heat units to the latter so that they are salvaged with the heat of the blown off products and the cost of supplying steam for this purpose correspondingly reduced.

Preferably a flow meter or other means will be employed by which supply of steam at the extraneous source will be regulated according to consumption in realizing the sev-

eral functions which characterize the invention.

In the accompanying drawings—

Figure 1 is a schematic view of a locomotive terminal equipped for practicing the present invention, locomotives being shown in the renovating stall, where the blowing off, washing out, and refilling of the boiler take place, and at the parking station where propelling pressure may be maintained by steam from the extraneous source while the locomotive is waiting for assignment.

Figure 2 is a section on the line 2^x—2^x of Figure 1 on a greatly enlarged scale; and

Figure 3 is a detail view on an enlarged scale of the equipment at the renovating stall.

Referring to Figure 1, A represents a main track, B a series of spur tracks leading therefrom, C a locomotive terminal house, D a series of renovating stations in said locomotive house, E a series of parking or waiting stations adapted to be assumed by locomotives under self propulsion by steam pressure developed in them at the renovating stations, F a series of spur tracks leading from the parking stations, and G a branch track connecting with all of the spur tracks F and connected through switching tracks H and I in a manner to present a locomotive forward in either direction on the track A. In addition to the foregoing, the locomotive terminal is equipped with blowoff, washout, refilling, and steam supplying apparatus now to be described, and it may be supplied with any other accessory apparatus or equipment such, for instance, as a coaling station K.

Referring to all the drawings, 1 represents a blowoff pipe adapted to receive blown off products from a locomotive boiler 2, through the pipe 1^a adapted to communicate with a steam dome, as through hose 1^b, controlled by valve 1^{b'}, or with the lower portion of the boiler through a hose 1^c, as may be desired; this blowoff pipe being connected to deliver the blown off products to a separator 3, whence the steam constituent escapes through a pipe 4 to a condenser 5 and thence, accompanied by an increment of water which reaches the condenser through the pipe 6, 100

flows through a pipe 7 to the filling tank 8; the water constituent of the blown off products being delivered through pipe 9 to washout tank 10. Water from washout tank 10 is advanced by a pump 11 through a pipe 12 to feed the drop 13 at the post 14 of the locomotive renovating station. Water from filling tank 8 is advanced by pump 15 through pipe 16 to supply drop 17 at said post 14.

In addition to the washout and refill water supply pipes the terminal is equipped with a live steam pipe 18 leading from any suitable stationary boiler 19 where steam can be economically and constantly generated, and this live steam pipe 18 supplies a steam drop 20 at the post 14. 21 represents a booster shown connected by the pipe 1^c with the drop 1^a of the blowoff pipe 1, and this booster receives the steam pipe 20 in such relation as will, for purposes of the present invention, cause acceleration of flow upward through the pipe 1^c. Box 21 is also provided with a connection 21^a which, for purposes of the present invention, is adapted to receive a pipe 22 leading from the lower portion 23 of the locomotive boiler for permitting liquid contents of the boiler to escape through pipe 22, box 21, and pipe 1^c to the blowoff line, as explained below. There are also present in the equipment of the apparatus a filling water pipe 17 adapted to discharge in the booster box 21, a gauge glass 25, and smoke jack 28 over the locomotive stack 29; but these have to do with the practice of refilling the locomotive boiler after the blowoff and in accordance with the direct steaming system described in U. S. Letters Patent No. 1,592,618 issued July 13, 1926, and therefore need not be further described in this case.

The connection 1^c for blowing off water from the boiler which is controlled at its upper end by valve 1^a is adapted to be attached to the injector box 21 so that discharge from said box will be delivered through the connections 1^c and 1^a to the blowoff pipe; and the connection 22 from the low part of the boiler is adapted to be attached to the connection 21^a, and through said connection deliver water from the boiler into the injector box 21, whence it will pass through connections 1^c and 1^a to the blowoff pipe; and if live steam pipe 20 be opened at this time, the flow of blowoff water will be accelerated and the time required for evacuation of the boiler correspondingly reduced. Inasmuch as the heat units of the steam used for this purpose are recovered in the condenser 5 and delivered to filling tank 8, this method of procedure is economical. Ordinarily, in blowing off the boiler, water will be evacuated from the point 23 directly into connection 1^c, and thence through connection 1^a to the blowoff pipe so long as internal boiler pressure is sufficient to insure a rapid evacuation of the boiler. But when the boiler pressure

drops to a point which greatly slows down the flow of water from the boiler, the connections will be shifted in the manner described, and evacuation of the remainder of the water will be boosted by the steam jet.

30 represents a flow meter or other suitable means for the steam line 18 having connection 31 with a damper 32 whereby it may maintain pressure in the boiler 19 commensurate with consumption of steam on the line 18.

I claim:

1. The improvement in the art of blowing off boilers and salvaging heat units from the contents thereof, consisting in blowing off liquid constituent of the boiler contents together with vaporous constituent thereof, accelerating the blowoff of the liquid discharge by injecting thereinto live steam under substantial pressure, separating the vapor constituent from the liquid constituent of the accelerated blown off material, condensing the vapors so separated, and storing the condensed vapors as refill water.

2. The improvement in the art of blowing off boilers and salvaging heat units from the blown off products, said improvement consisting in discharging vapor constituent of the boiler contents from a portion of the boiler above the water line and both vapor constituent and liquid constituent of the boiler contents from the boiler below the water line, accelerating the flow of liquid discharge by injecting thereinto live steam under substantial pressure, separating both the vapor resulting from the injected steam and the vapor boiler constituent, which accompanies the liquid, from the said liquid, condensing all of the vapors, and storing the condensed vapors, as refill water.

Signed at Chicago, Illinois, this 23 day of January, 1923.

SPENCER OTIS.
